UNITED STATES PATENT OFFICE.

WILLIAM HENRY MORGAN, OF ALLIANCE, OHIO.

RAILROAD-TRACK CONSTRUCTION.

1,123,782.

Specification of Letters Patent.

Patented Jan. 5, 1915.

Application filed May 22, 1914. Serial No. 840,313.

To all whom it may concern:

Be it known that I, WILLIAM H. MORGAN, resident of Alliance, in the county of Stark and State of Ohio, have invented certain 5 new and useful Improvements in Railroad-Track Construction; and I do hereby declare the following to be a full, clear, and exact description of the invention, such as will enable others skilled in the art to which 10 it appertains to make and use the same.

My invention relates to an improvement in railroad track construction, the object being to provide means for so supporting the rails that the load will be distributed over 15 a series of ties, thereby permitting the use of smaller rails than can be safely used on a track in which the rails are supported at intervals on the ties.

With this object in view my invention 20 consists in the parts and combination of parts as will be more fully explained and pointed out in the claims.

In the accompanying drawings, Figure 1 is a view in perspective of a section of a 25 track embodying my invention; Fig. 2 is a view in vertical section through a rail and its supporting girder and showing the supporting means for the latter; Fig. 3 is a view similar to Fig. 2, showing the rail insulated from the tie; Fig. 4 is an end view and Fig. 5 a side view of the construction shown in Fig. 2 applied to a wood tie; Fig. 6 is a view of a section of a tie showing the rail supporting chair and rail locking clips; 30 Figs. 7 and 8 are views of the rail locking clip and Figs. 9 and 10 are views of modifications.

1 represents the tie, preferably made of steel, I-shape in cross section, and provided 40 with a base flange 2 wider than the top flange 3, the said base flange being preferably inclined downwardly as shown in Fig. 1 so as to form a housing under, or within which, the ballast will pack when tamped. 45 Secured to the top flange of the tie, are the chairs, each of which is composed of two sections 4 as shown in Fig. 6. These chairs are preferably made of sheet steel pressed or stamped into shape, and each comprises 50 an upright member 5 terminating at its top in a shoulder 6, and upwardly projecting flange 7, the free upper edge of which latter is turned inwardly toward the rail, and a base member 8, all of said parts being integral. Each chair section is strengthened 55 and reinforced by the rib or brace 9, which

latter is stamped or pressed out from the upright base member and shoulder, and extends from adjacent the outer edge of the base member to approximately the outer 60 edge of the shoulder, and operates to prevent any outward deflection or collapsing of the chairs under any stress to which they may be subjected. The base member of each section of the chair is provided at its side 65 edges with the flanges 10 which are bent around under the top flanges 3 of the tie, and lock the parts or sections of the chair in place. If desired the two sections of a chair may rest on a plate 11, as shown in 70 Figs. 4 and 5. This plate has upturned flanged ends 12, which engage the outer edges of the base member of the chair sections and operate to prevent the possibility of any separation of the sections. When 75 used on a metal tie, the parts including the plate will be locked to the tie by the flanges 10 of the chair section engaging the top flange of the tie, and when secured to a wood tie, as in Figs. 4 and 5, they will be 80 secured by spikes or screws 12^a passing through the base plates and plate 11 and into the tie.

The girders or stringers 13 are preferably old steel rails, placed head down between the upright members 5 of the chair, with their base flanges resting on the locking clips 14 seated on the shoulders 6 of the chair. Any other form of girder, will however answer the purpose, but I prefer old 85 rails, on account not only of their cheapness, but also because of the superior metal of which they are made. The girders or stringers 13 are suspended between the sections of the chairs, clear of the ties and 90 support the rails throughout the length of the latter, except possibly at switches, and are arranged to break joints with the rails, so that a joint in the rails, and a joint in the girders will not come between the same ties. 95 The ends of the girders are connected by fish plates 15^a, and the ends of the rails are also connected by fish plates, and they are both secured to the chairs by the locking clips 14. The clips are approximately as 100 long as the tops of the chairs, and each is approximately U-shape, the lower member being longer than the upper member, and provided centrally with a tongue 15 integral therewith, the portion of the lower 105 member of the clip which forms in effect a continuation of the tongue, being depressed 110

below said lower member so as to form a projection, which, entering the recess in the shoulder 6 formed by stamping or pressing out the rib or brace 9, operates to lock the clip in place against endwise movement. The free ends of the tongues 15, extend downward between the two members of the chair and bear with a spring pressure against the opposite sides of the web of the girders 13, which operates to not only hold the tongue 15 within the recess formed by stamping up rib or brace 9 from shoulder 6, and lock the clip against endwise displacement, but it also holds the clip solidly against the top flange of the girder with the upper member or lip of the clip over the base flange of the rail. The upper free ends of the flanges 7 of the chair sections, are curved inwardly to slightly overhang the clip, so that when the clips are in place they are positively held against vertical displacement. The upper members of the clips overhang the base flanges of the rails without contacting with the same, thus leaving the rails and girders loosely seated on the lower members of the clips, and free to move lengthwise without opposition, and also free to move vertically a limited distance. The only pressure to which a rail is subjected other than downward, is an outward one, which is taken care of by the side flanges 7 of the chair, hence there is theoretically, no tendency of the rails to tip, but as the ends of the clips overhang the base flanges of the rails, and are only removed therefrom a limited distance, tipping to anything like a dangerous extent will be absolutely prevented by the overhanging members of the clips.

The clips are struck up from sheet steel, and are inserted endwise, or in the direction of the length of the rails, and preferably after the girders and rails have been placed on the chairs, and each is provided on its inner face in the plane of the base flange of the rail, with a series of projections 17, the projections on one clip being greater than those on its companion clip, so that by removing and reversing their positions the rail can be adjusted or moved toward the other rail of the track to compensate for wear. In the construction shown in Fig. 2, the larger projections 17 are at the left, or at the inner side of the rail. If now the inner face of the head of the rail should wear sufficiently to affect the gage of the track or necessitate re-adjustment of the rails, it can be readily and quickly done by removing the clips and placing those with the longer projections at the outer side of the rail, thus shifting the rail a distance approximately equal to the difference in the length of the projections. It will be readily seen that this same result can be accomplished by providing one clip only of each pair with projections.

With the construction above described, the load is distributed equally on and between a series of ties, and does not fall wholly on the ties in the vertical plane of the load, and by using old rails, instead of built up girders, all objections to riveted structure is avoided. By supporting the rails on suspended girders, a lighter rail can do the work of a much heavier rail that is supported only at intervals, so that with my improvement much smaller rails can be safely used with the heavy rolling stock that is now rapidly coming into use, and which could not possibly be used if they were supported only at intervals. By the use of girders or stringers in conjunction with cross ties, I distribute the rolling load uniformly over the cross ties; considerably reduce the pressure per square foot between the ties and ballast and also reduce the cost of maintaining the road bed owing to the fact that less retamping will be required. Again the construction is absolutely clear of external projections which could be engaged and knocked off by the wheels in the event of a derailment, and by changing the shape of the cross sectional area of the clips, rails of all sizes and weights may be used without disturbing the chair, ties or ballast. When it is necessary to insulate the rails from the ties, it may be done as shown in Fig. 3 by inserting insulating material 18 between the clip, and the shoulder and flange supporting the latter, or the insulating material may be inserted between the tie and chair sections as shown in Fig. 9. Again the improvement may be used with metal ties of the hollow variety, by simply passing the side flanges 10 of the chair sections through slots in the top of the tie and then bending the flanges up against the under face of the top as shown in Fig. 10.

It is evident that many slight changes might be resorted to in the relative arrangement of parts shown and described without departing from the spirit and scope of my invention. Hence I would have it understood that I do not wish to restrict myself to the exact construction and arrangement of parts shown and described but,

Having fully described my invention what I claim as new and desire to secure by Letters-Patent, is:—

1. In railroad track construction, the combination of ties, two part chairs each independently secured to said ties, girders suspended from said chairs and resting between the parts thereof, rails on the top faces of the girders, and means carried by the chairs for locking the girders and the rails in place.

2. In railroad track construction, the combination of ties, two part chairs secured on the tops of the ties and projecting above the same, rail locking means loosely supported

- on each part of the chair, a girder suspended from said locking means and resting between the parts of the chair, and a rail on the top of said girder and retained thereon 5 by the locking means.
3. In railroad track construction, the combination of ties, chairs thereon, rail locking means on the chairs, girders resting on said rail locking means and holding the same in 10 place and rails on the girders.
4. In railroad track construction, the combination of ties, chairs thereon, connected girders carried by the chairs, rail locking means also carried by the chairs and locked 15 thereto by the girders and rails resting on the girders and held against displacement by the rail locking means.
5. In railroad track construction, the combination of ties, chairs thereon, each chair 20 composed of two shouldered parts, rail locking means resting on the shoulders of the chair, girders suspended from said rail locking means and rails resting on the girders.
6. In railroad track construction, the combination of ties, chairs on the ties, rail locking means carried by the chairs, girders suspended within the chairs and supported on 25 said rail locking means, and rails on said girders.
- 30 7. In railroad track construction, the combination of ties, chairs thereon, each chair composed of two upright members each having a shoulder at its upper end, rail securing means on said shoulders, flanged girders, the top flanges of which rest 35 on said rail securing means, and rails on the girders, the top flanges of the girders and base flanges of the rails being overlapped by said rail securing means.
- 40 8. In railroad track construction, the combination of ties, chairs thereon, each chair composed of two upright members, each having a shoulder at its upper end, U-shaped locking clips resting on said shoulders, girders supported on said clips, and rails supported on the girders with their base flanges 45 overlapped by the clips.
9. In railroad track construction, the combination of ties, chairs thereon, each chair 50 composed of two upright members each having a shoulder at its upper end, U-shaped locking clips resting on said shoulders, the lower member of each clip having an inwardly projecting tongue, girders resting 55 on the lower member of the clips and engaged by the inwardly projecting tongues of each pair of clips, whereby the upper members of the clips are forced inwardly toward each other, and rails resting on the 60 girders, the base flanges of the rails being overlapped by the upper members of the clips.
10. In railroad track construction, the combination of ties, chairs thereon, each chair composed of two upright members 65 each having a shoulder at its upper end, and each having a recess in its inner face, rail fastening clips seated on said shoulders and each having a projection to enter the recess in its chair member, girders resting on said clips, and rails resting on the girders and held in place thereon by the clips.
11. In railroad track construction, the combination of ties, chairs thereon, each 70 chair composed of two uprights each having a shoulder and an upwardly and inwardly turned flange at its upper end, U-shaped clips seated on the shoulders and backed up by the flanges, girders supported 75 on said clips and rails resting on the girders and locked against displacement by the clips.
12. In railroad track construction, the combination of ties, chairs thereon, each 80 chair composed of two upright members each having a shoulder at its upper end, a pair of U-shaped clips for each chair, one clip of each pair having inward projections to engage the edge of the base flange of the 85 rail, girders supported on said clips and rails resting on the girders and held in place by the clips.
13. In railroad track construction, the combination of ties, chairs thereon, each 90 chair composed of two disconnected members struck up from sheet metal and each provided at its upper end with a shoulder, U-shaped clips resting on said shoulders, girders suspended from the clips, and rails 95 resting on the girders and held in position thereon by the clips.
14. In railroad track construction, the combination of ties, two part chairs secured 100 to the ties, girders suspended from and between the parts of the chairs, rails on the girders, and means for insulating the rails from the ties.
15. In railroad track construction, the combination of ties, two part chairs secured 105 to the ties, each part of the chair having a shoulder at its upper end, locking clips supported on the shoulders, girders resting on said clips and suspended between the parts of the chairs, and rails on said girders and 110 held in place by the clips and the chairs.
- In testimony whereof, I have signed this specification in the presence of two subscribing witnesses.

WILLIAM HENRY MORGAN.
